UNITED STATES PATENT OFFICE.

GEORGE W. THOMAS, OF BALTIMORE, MARYLAND.

ELEVATOR ATTACHMENT.

SPECIFICATION forming part of Letters Patent No. 308,010, dated November 11, 1884.

Application filed April 14, 1884. (No model.)

To all whom it may concern:

Be it known that I, GEORGE W. THOMAS, of the city of Baltimore and State of Maryland, have invented certain Improvements in 5 Elevator Attachments, of which the following is a specification.

This invention relates to certain improvements in a device to be applied to one of the upright posts of an elevator, or to a wall adjacent to the elevator, to hold down the check-cord, and thereby release the brake mechanism and admit of the free movement of the elevator-platform, as will hereinafter fully appear.

15 In the accompanying drawings, forming a part hereof, Figure I is an exterior side view of the invention applied to one of the upright posts of an elevator. Fig. II is a front view of Fig. I. Fig. III is a sectional view of Fig. 20 I. Fig. IV is also a sectional view of the invention by illustrating a modification in the construction thereof.

A is one of the upright posts of the elevator, and B a frame bolted to the post A at a point 25 above the upper floor of the building. The frame B has a fixed jaw, a, with a hollowed inner surface where in contact with the cord, and a movable jaw, C, also having a hollowed surface which is connected to the frame B by means of a spring, D, as shown. The hollowed faces of the jaws a and C form a channel, b, (shown in Figs. III and IV,) through 30 which passes the check-cord D', which cord upon being pulled down and held releases the friction-clutch or brake mechanism of the elevator, and allows the platform to be raised or lowered.

E is a ball on the check-cord D', which as the said cord is pulled forces back the jaw and passes beneath it, thus preventing the 40 upward movement of the cord.

F is a releasing-cord having a weight, e, at its lower end, which extends to near the lower floor of the building. The upper end of the cord F passes over a sheave, d, and is attached to a lug, f, on the back of the movable jaw C.

Supposing the elevator-platform is to be raised or lowered, the check-cord D' is pulled down until the ball E catches underneath the 50 jaws a and C, when the clutch mechanism of the elevator is rendered inoperative. Supposing again that the platform is ascending or descending, and it is required to be stopped at any one of the floors, the releasing-cord F 55 is pulled, which draws back the jaw C and allows the ball E to pass it and the check-cord to assume its original position.

In Fig. IV a weighted lever is substituted for the spring D.

60 I claim as my invention—

In combination with the stationary upright post A of the elevator, the frame B, having the fixed jaw a and the yielding jaw C, the check-cord D', having the ball E and the releasing-cord F, the upper end of which passes over a sheave and is attached to the said yielding jaw, substantially as specified.

GEORGE W. THOMAS.
